PROPELLER

Bernard C. Freise, St. Louis County, Mo.

Application July 2, 1936, Serial No. 88,538

2 Claims. (Cl. 115—33)

My invention has relation to improvements in propellers and it consists in the novel features of construction more fully set forth in the specification and pointed out in the claims.

5 The principal object of the invention is to provide a propeller especially adapted to boats that operate by reciprocating movement through the water so as to push the vessel forward with the movement in one direction while moving idly in 10 the opposite direction, the whole while being submerged. The continual submergence of the propeller assures that at no time will any part thereof have to be lifted through the water, with a consequent lowering of the efficiency thereof.

15 A further object of the invention is to combine the functions of a rudder with the propeller by mounting the same for rotation through an angle of 360 degrees. The rotation of the propeller makes it possible to propel the vessel both forward and backward.

Other advantages will be more readily apparent from a detailed description of my invention in connection with the accompanying drawing, in which:

25 Figure 1 is a side elevation of a model boat, to the stern of which my improved propeller is applied; Fig. 2 is a top plan of the same; Fig. 3 is a rear elevation thereof; Fig. 4 is an enlarged top plan of the propeller with parts broken away; 30 Fig. 5 is a vertical cross-section of the propeller taken on the line 5—5 of Fig. 3; Fig. 6 is a section similar to that shown in Fig. 5 with part of the propeller in elevation and the propeller proper shown rotated through an angle of 180 degrees 35 so as to propel in the opposite direction to that in which it would propel as shown in Fig. 5;

Figure 7 is a cross-sectional detail through the steering staff taken on the line 7—7 of Fig. 2.

40 Referring to the drawing, B represents a conventional boat (which may be either a toy or a commercial vessel) provided with an engine or motor E within the engine housing H. No attempt is made to show any particular type of engine as the engine will depend largely upon the 45 purposes for which the boat is used. I represents the engine drive shaft, on the ends of which are combined fly wheels and cranks 2, 2 to each of which is pivotally connected a crank rod 3, to the free end of which, in turn, is connected a connecting rod 4. Thus, there are a pair of connecting rods 4 supported on suitable bearings 5, 5 and 6, 6, the latter passing through the stern of the boat. My improved propeller P is carried by the ends of the connecting rods 4, 4 which 55 are riveted or otherwise secured to brackets 7, 7

fixed at the ends of cross member 8 of a rectangular frame 9. A pair of guide rods 10, 10 are each secured at one end to the lower edge of the side members of the frame 9 and are slidably mounted in bearings 11, 11 fixed to the keel 12 of the boat.

5 The propeller P comprises a rectangular frame 13 pivotally mounted in the cross member 8' of the frame 9 by means of a gudgeon 14 and a stub shaft 15 which has bearing in member 8 of the frame 9.

Obviously, the gudgeon 14 and stub shaft 15 are in vertical alignment so that the frame 13 may be rotated on a vertical axis within the frame 9. There are a plurality of overlapping propeller members 16, 16, etc., each of which is pivotally mounted in the side members 17, 17 of frame 13, the lowermost of said propeller members 16, bearing against a flange 18 in frame 13 when in lowered or vertical position. The arrangement of the propeller members 16 is similar to that of ventilating louvers as they are capable of swinging upwardly (dotted position Fig. 5) to provide free passage through the frame 13, but when swung downwardly they completely close the opening through said frame. The upward movement of the propeller blades 16 is limited by a bar 19 extending from the top to the bottom of the frame 13 at the rear thereof.

20 A gear 20 is fixed on the end of stub shaft 15 and a pinion 21 is fixed on the end of a shaft 22 mounted in brackets 23, 24, the former projecting upwardly from frame 9 while the latter projects upwardly from the bottom of the boat B. The shaft 22 is provided with a spline 25 and the 25 shaft is slidably mounted in a slotted sleeve 26 supported by bracket 24 and a suitable bearing 27 in the end of the boat. The inner end of sleeve 26 has a steering wheel 28 fixed to it so that by turning said wheel, the sleeve 26 and shaft 22 30 may also be turned to effect rotation of pinion 21 and gear 20, and of course, the frame 13 carrying the propeller blades 16. By virtue of the rotation of the frame 13, the propeller blades may 35 be turned so as to operate in either direction, 40 that is, either forward or backward or at any angle in between.

45 In order to more rigidly hold the propeller P, a pair of side braces 29 extend between the sides of frame 9 and connecting rods 4.

50 The manner of operation of my improved propeller is as follows:

55 When the engine shaft 1 is rotated, the wheels 2, 2 will also be rotated, causing cranks 3, 3 to reciprocate connecting rods 4, 4. The propeller

P will also be reciprocated since it is carried by the connecting rods 4, 4 and as it moves backward and forward in the water, it will give periodic impulses to the boat since the propeller blades 5 16 push against the resistance of the water on the backward movement of the propeller and rise to their upper positions to permit the water to flow freely through the propeller on the forward movement thereof. Obviously, the speed with 10 which the propeller P is reciprocated will control the speed of the boat's travel. The steering of the boat is accomplished by rotating the entire frame 13 of the propeller P through the steering wheel 28 and intermediate connection to said frame. If it is desired to reverse the movement of the boat, the steering wheel 28 is turned sufficiently to rotate the frame 13 through an angle of 180 degrees, whereupon the propeller blades 16 will operate in the opposite direction to that just 15 described.

While I have illustrated my invention applied to a boat, I do not wish to be restricted to a propeller capable of use only on boats. The principle of the invention is equally adaptable for propellers of aircraft and I wish it distinctly under- 20 25

stood that I contemplate such application of the invention.

Having described my invention, I claim:

1. A propeller comprising a frame, means connected therewith for imparting reciprocating motion thereto, a second frame mounted for rotation within the first mentioned frame, a plurality of propeller blades pivotally mounted in overlapping relation within the second frame for oscillation therein, and means for confining the oscillations of the blades within an angle of 90 degrees. 5 10

2. A propeller comprising a frame, means connected therewith for imparting reciprocating motion thereto, a second frame mounted for rotation within the first mentioned frame, a plurality of propeller blades pivotally mounted in overlapping relation within the second frame for oscillation therein, means for confining the oscillations of the blades within an angle of 90 degrees, a steering wheel, suitable gearing on said second frame, and an extensible shaft between said wheel and gearing whereby rotation of the steering wheel imparts rotation to said frame. 15 20
